UNITED STATES PATENT OFFICE.

WILLIAM A. TODD, OF POINT PLEASANT, NEW JERSEY.

MACHINE FOR MAKING BUILDING-STONES.

1,027,935.

Specification of Letters Patent.

Patented May 28, 1912.

Application filed August 5, 1910, Serial No. 575,710. Renewed October 20, 1911. Serial No. 655,748.

To all whom it may concern:

Be it known that I, WILLIAM A. TODD, a citizen of the United States, and a resident of Point Pleasant, in the county of Ocean and State of New Jersey, have invented a new and Improved Machine for Making Building-Stones, of which the following is a full, clear, and exact description.

The object of the invention is to provide a new and improved machine for producing building stones from blocks of concrete, cement or other plastic materials, the building stones having different shaped front and rear faces to resemble natural stone building blocks, and when used in a building or a house break the monotony of the facade of the building or house.

For the purpose mentioned, use is made of a series of pressure devices encircling the block, and exerting simultaneously inward pressure on the block surface on a line around the said surface, to sever the block along the said line and leave the severed faces in a natural broken condition.

25 A practical embodiment of the invention is represented in the accompanying drawings forming a part of this specification, in which similar characters of reference indicate corresponding parts in all the views.

20 Figure 1 is a plan view of the machine; Fig. 2 is a sectional side elevation of the same on the line 2—2 of Fig. 1; Fig. 3 is a similar view of the same on the line 3—3 of Fig. 1; Fig. 4 is a plan view of one of the 25 plates, its slide and the means for moving the same; Fig. 5 is a plan view of a set of plates for severing a block into stones having angular sides; Fig. 6 is a like view of a set of plates for severing a square block into square stones; Fig. 7 is a similar view of a set of plates for severing a triangular block into triangularly shaped stones; and Fig. 8 is a plan view of one of the half-nuts and the parts associated therewith.

45 A suitably constructed frame A is provided with a central opening B for the passage of a block C made of concrete, cement or other plastic material, the block being operated upon before it is completely set or 50 in dried condition. The block is suspended by clamps D from a cross head E' forming part of a block carrier and feeder E for intermittently lowering the block so that the same can be severed into stones C', as 55 indicated in Fig. 2, and as hereinafter more fully described. A series of pressure plates

F are adapted to engage the block C with their pressure edges, so as to completely encircle the block C. On moving the plates F inward the pressure edges exert an inward pressure on the block C along a line surrounding the block C, until the stone C' is severed from the block C and drops off, the severed faces of the stone and block appearing in a condition as if naturally broken (see Fig. 2).

The plates F at their pressure edges range in the same plane, and the plates are bolted or otherwise secured to slides G, mounted to slide in suitable guideways H, arranged on the main frame A, the said slides G and their plates F moving readily toward and from the center of the opening B, in which the block C is centrally suspended, as plainly indicated in the drawings. Each of the slides G is provided with a guideway G', engaged by a bearing I in the form of an open frame (see Fig. 4), into which extends a cam J secured or formed on a vertically-extending shaft J', journaled in suitable bearings on the main frame A. On the upper end of each cam shaft J' is secured a pinion J² in mesh with a gear wheel K, mounted to turn in suitable bearings A' arranged on the main frame A, concentrically with the opening B, and the said gear wheel K is in mesh with a pinion L attached to a shaft L', journaled in the main frame A, and provided with a pulley L² connected by a belt L³ with other machinery for imparting a continuous rotary motion to the shaft L'. Now when the machine is running and the shaft L' is rotated, then a rotary motion is given by the pinion L to the gear wheel K, which in turn rotates the several pinions J², thus turning the cams J and thereby moving the slides G simultaneously inward or outward, according to the direction in which the shaft L is turned. Thus the several plates F are simultaneously advanced to engage their pressure edges with the sides of the block C, to sever a stone C' from the said block, as before mentioned, and shown in Fig. 2.

100 In order to permit accurate setting of each plate F, its slide G is independently adjustable in its guideway H, and for this purpose use is made of two screw rods N, mounted to turn in the slide G and screwing in the corresponding bearing I, the outer ends of the screw rods N being provided with gear wheels N' in mesh with each

other, one of the gear wheels having a handle N^2 , adapted to be taken hold of by the operator for turning the gear wheels N' to revolve the screw rods N and thus shift the 5 slide G and its plate F inward or outward, to bring the pressure edge of the plate F into proper position relative to the block C . It is understood that this adjustment is made when the machine is at a standstill, 10 and the bearing I is held against movement by its cam J , so that on turning the screw rods N the slide G and its plate F are moved inward or outward, according to the direction in which the screw rods N are 15 turned, by the operator having hold of the handle N^2 .

In order to permit accurate setting or adjusting of the slides G and the plates F , scales O , representing linear measurement, 20 are marked on the slides G (see Fig. 1), the marks on the scales indicating along the outer edges of the guideways H , to enable the operator on turning the handle N^2 to move the corresponding slide G the desired 25 distance inward or outward, as the circumstances may require. As shown in the drawings, the pressure plates F overlap, so that the device can be readily adjusted for severing blocks of different sizes and shapes.

30 The block carrier and feed E for intermittently lowering the block C , at the time the slides G and their knives F move outward, may be of any approved construction, and, as shown, consists of a cross head E' 35 provided with bearings E^2 for the passage of vertically-disposed screw rods P , journaled in suitable bearings arranged on the overhead structure A^2 forming part of the frame A . The screw rods P are adapted to 40 be engaged by half nuts Q , mounted to turn on pivots Q' , arranged on the top of the cross head E' , and the said half nuts Q are normally held in contact with the screw rods P by springs Q^2 pressing the said half 45 nuts Q . The half nuts Q are connected with chains R extending inwardly and passing around pulleys R' journaled on top of the cross head E' , the chains connecting with a chain R^2 , under the control of the operator, 50 for swinging the half nuts Q out of engagement with the screw rods P whenever it is desired to raise the cross head E' after a block C has been severed into building stones C' by the successive action of the 55 knives F , as previously explained.

The upper ends of the screw rods P are provided with sprocket wheels P' , connected with each other by a sprocket chain P^2 , and on one of the screw rods P is secured a pinion S in mesh with a mutilated gear wheel S' , secured on the upper end of a shaft L^4 , forming an extension of the driving shaft L' previously mentioned, so that when the shaft L' is rotated an intermittent turning movement is given to the

50 screw rods P , to intermittently lower the cross head E' , and consequently the clamp D and the block C , at the time the knives F move outward away from the block C . During the time that the plates F move inward in engagement with the block C , the toothless portion of the mutilated gear wheel S' is passing the pinion S , so that the latter remains at a standstill and consequently the feeding of the block C is suspended during the severing operation of the stone C' from the block C . When the last stone has been severed from the block C , the rotation of the shaft L' is stopped, and then the operator pulls on the chain R^2 , so as to 55 disengage the half nuts Q from the screw rods P . When the half nuts are disengaged from the screw rods the cross head E' can then slide freely on the screw rods and is moved upward by the operator into uppermost position, after which the operator releases the chain R^2 , so as to allow the springs Q^2 to return the half nuts Q , with a view to reengage the half nuts with the screw rods P and thereby support the cross head E' in 60 an uppermost position. A new block C is now placed in position on the clamp D , after which the machine is again started up and the above described operation is repeated.

In Figs. 1, 2 and 3 is illustrated a machine having four plates F , for severing a block C , which is square in cross section, but for different shaped blocks C the plates are differently arranged; for instance, as 100 shown in Fig. 5, the two opposite plates F' have their edges at angles to the pressure edges of the other set of plates F^2 , to permit of severing blocks of rectangular shape. For square blocks C , a pair of plates F^3 , 105 may be used for severing the block into square stones, but in this case each plate F^3 has angular pressure edges F^4 , as will be readily understood by Fig. 6.

For severing stones C' from blocks C of 110 triangular shape in cross section, use is made of two plates F^5 and F^6 , of which the plate F^5 has a straight pressure edge F^7 , while the plate F^6 has a V-shaped pressure edge F^8 , it being understood that in both 115 cases (see Figs. 6 and 7), the two plates F^5 , F^3 or F^5 and F^6 are moved toward each other to produce the desired result.

It is understood that in all cases, a continuous simultaneous pressure is exerted on the block C from all sides, by the pressure edges of the plates, the penetration of the pressure edges into the block being but minute, but the pressure being sufficient to cause a severing of the stone from the block with the result that the severed faces appear in the same condition as a fractured stone surface, and hence the faces of the stones produced from the blocks vary one from the other, and hence when such stones are used 120 125 130

for forming the wall of a building or a house, the façade thereof is not monotonous, as is naturally the case in buildings or houses built of bricks or concrete blocks which are alike on their faces.

Having thus described my invention, I claim as new and desire to secure by Letters Patent:

1. A machine for severing building stones from blocks, comprising a frame, having a central opening for the passage of a block to be severed, a block carrier and feeder for supporting the block and feeding it intermittently in the said opening, plates having their pressure edges encircling the block in the same plane, slides carrying the said plates and mounted to slide in the said frame, and means for imparting a simultaneous inward movement to the said slides to cause the said pressure edges to exert pressure on all sides of the block to sever the same and leave the severed faces in a naturally broken condition.

2. A machine for severing building stones from blocks, comprising a frame, having a central opening for the passage of a block to be severed, a block carrier and feeder for supporting the block and feeding it intermittently in the said opening, plates having their pressure edges encircling the block in the same plane, slides carrying the said plates and mounted to slide in the said frame, the said slides being provided with guideways, bearings arranged in the guideways of the said slides, revolute shafts provided with cams for engaging the bearings to move the said slides, pinions on the cam shafts, and a gear wheel meshing with the pinions for simultaneously turning the said cams to impart simultaneous movement to the said slides and their plates.

3. A machine for severing building stones from blocks, comprising a frame, having a central opening for the passage of a block to be severed, a block carrier and feeder for supporting the block and feeding it intermittently in the said opening, plates having their pressure edges encircling the block in the same plane, slides carrying the said plates and mounted to slide in the said frame, bearings in slidable engagement with the said slides, manually-controlled means for adjusting the bearings and slides one relative to the other, revolute shafts provided with cams engaging the said bearings, pinions on the cam shafts and a gear wheel meshing with the pinions for simultaneously turning the said cam shafts.

4. A machine for severing building stones from blocks, comprising a frame, having a central opening for the passage of a block to be severed, a block carrier and feeder for supporting the block and feeding it intermittently in the said opening, plates having their pressure edges encircling the block in

the same plane, slides carrying the said plates and mounted to slide in the said frame, bearings in slidable engagement with the said slides, a pair of screw rods mounted to turn in the slides and screwing in the said bearings, meshing gear wheels secured on the said screw rods, revolute cams engaging the said bearings, pinions on the said cams, and a revolute gear wheel in mesh with the said pinions.

5. A machine for severing building stones from blocks, comprising a frame having a central opening for the passage of a block to be severed, a block carrier and feeder for supporting the block and feeding it intermittently in the said opening, plates having their pressure edges encircling the block in the same plane, slides carrying the said plates and mounted to slide in the said frame, revolute cams for moving the said slides, pinions on the said cams, and a revolute gear wheel in mesh with the said pinions to simultaneously move the said slides and their plates.

6. A machine for severing building stones from blocks, comprising a frame having a central opening for the passage of a block to be severed, a block carrier and feeder for suspending the block and feeding it intermittently downward in the said opening, and pressure plates for centering the suspended block in the opening and for exerting simultaneous inward pressure on the block surface.

7. In a machine for severing building stones from blocks, a frame having a central opening, means for suspending a block and feeding it intermittently downward in the said opening, and severing means for exerting pressure on all sides of the block simultaneously to sever the same.

8. A machine for severing building stones from blocks, comprising a frame having an opening for the passage of a block to be severed, a block carrier from which the block is suspended, a vertically disposed driving shaft, means operated from the shaft for intermittently lowering the block carrier and block, and means actuated from the driving shaft for exerting pressure on all sides of the block simultaneously to sever a stone from the block after each downward movement of the block.

9. A machine for severing building stones from blocks, comprising a frame having an opening for the passage of a block to be severed, a block carrier provided with means for suspending the block, a driving shaft, means actuated from the driving shaft for intermittently lowering the block carrier to feed the block intermittently downward in the said opening, pressure plates having their pressure edges encircling the lower part of said block, and means actuated from said driving shaft, after each

downward movement of the block, for imparting simultaneous movement to the said plates to sever the block.

10. A machine for severing building stones from blocks, comprising a series of pressure plates encircling the block in approximately the same plane and mounted to slide toward and from the block, means for imparting simultaneous movement to the pressure plates to cause them to exert pressure on all sides of the block to sever a stone from the block, a carrier for the block, and mechanism for intermittently moving the carrier to feed the block intermittently between the said pressure plates.

11. In a machine for severing building stones from blocks, a block carrier and feeder for suspending the block and feeding it downward, and pressure devices for centering the suspended block and for exerting simultaneous inward pressure on all sides of the block surface to sever a stone from the block, and leave the severed faces in a naturally broken condition, the said devices overlapping to allow of adjustment for blocks differing in shape and size.

12. A machine for severing stones from blocks, comprising means for suspending a block and feeding it intermittently downward, a series of plates having their edges encircling the block in approximately the same plane, slides carrying the said plates, guideways in which the slides are loosely guided, means for shifting the said slides inward or outward independent of each other, and means for simultaneously extending the said slides to cause the edges of the plates to act simultaneously on all sides of the block surface to sever the block and leave the severed faces in a naturally broken condition.

13. In a machine for severing building stones from blocks, a series of pressure de-

vices encircling the block in approximately the same plane, slides carrying the said pressure devices, the slides being provided with guideways, bearings arranged in the guideways of the slides, means connected with the bearings and slides for adjusting the slides relative to the bearings, and means engaging the said bearings for imparting simultaneous movement to the said slides and the pressure devices.

14. In a machine for severing building stones from blocks, a frame having an opening for the passage of a block to be severed, means for supporting the block and feeding it intermittently in the said opening, a series of severing devices surrounding the block and mounted to slide in the frame, and means for simultaneously moving the severing devices inward after each feeding movement of the block to sever a stone from the block.

15. In a machine for severing building stones from blocks, a block carrier for supporting a block, a series of severing plates surrounding the block and mounted to slide toward and from the block, a driving shaft, means actuated from the driving shaft for moving the said severing plates inward and outward, and mechanism actuated from said driving shaft for feeding the block carrier and block at the time the severing plates are moved outward away from the block, the said driving shaft moving out of operative connection with the said mechanism at the time the severing plates are moved inward to sever the block.

In testimony whereof I have signed my name to this specification in the presence of two subscribing witnesses.

WILLIAM A. TODD.
